UNITED STATES PATENT OFFICE.

ALVIN S. KLEINSMITH, OF OREGON CITY, OREGON.

PRUNING APPLIANCE.

No. 927,359.

Specification of Letters Patent.

Patented July 6, 1909.

Application filed November 27, 1908. Serial No. 464,555.

To all whom it may concern:

Be it known that I, ALVIN S. KLEINSMITH, a citizen of the United States, residing at Oregon City, in the county of Clackamas and State of Oregon, have invented certain new and useful Improvements in Pruning Appliances; and I do hereby declare the following to be a full, clear, and exact description of the invention, such as will enable others skilled in the art to which it appertains to make and use the same.

My invention relates to new and useful improvements in pruning shears or appliances and my object is to provide means for pruning or severing the limbs or branches of trees that may be desired to be discarded.

A further object is to carry out this end in a simple manner and to provide such means at little expense and a further object is to provide for the ready actuation of such means.

My invention, therefore, consists of the novel combination and arrangement of parts including their construction, substantially as hereinafter more fully disclosed and defined by the claims.

In describing the invention in detail, reference will be had to the accompanying drawings forming part of this specification, wherein like reference characters designate corresponding parts in the several views, and wherein—

Figure 1 is a side elevation of the device with the jaws of the instrument in their initial or normal position. Fig. 2 is a horizontal section as seen on line 2—2, Fig. 1. Fig. 3 is a detached perspective view of the attaching bracket for the manually actuated lever, and Fig. 4 represents a blank from which the actuating lever or attaching member is formed.

In carrying out my invention, I provide a suitable handle or staff 1, adapted to be suitably grasped at its lower end by the operator and having secured preferably thereto, by the aid of a suitable ferrule 2, a stationary hook-shaped jaw or blade 3, preferably in outline resembling the bill or beak of a bird, said jaw or blade being fixed to the handle or staff 1 and in outline, as noted, is adapted to readily engage the limb or branch of a tree, as in applying it for effecting the cutting action. Pivotal secured to the inner terminal of the blade 3, is an additional blade 4, having an arcuate cutting edge opposed to and facing the cor-

responding cutting edge of the first-referred-to cutter or blade and also having projecting beyond its pivotal or fulcrum point, an arm for imparting the requisite leverage thereto in effecting the severing operation. To the outer end of the lever portion or arm of said cutter or blade 4 is suitably connected the upper end of a wire rod member 5, passing through and having its movement controlled by an eye or staple 6 projecting from the handle or staff 1 about mid-way the length of said wire-rod, and to the lower end of said wire rod is connected the angular shank 7 of a manually actuated lever 8. Said shank member is bent at less than a right angle to the handle-portion proper of said lever and suitably pivoted in a bracket or attaching member 9, its pivot 8^a being received in alining apertures of parallel outstanding ears 9^a struck up from said bracket. The attaching member or bracket 9 has formed therewith at its corner edges, sharpened lateral extensions 12 arranged to stand at an angle to the plate member or portion of said bracket and adapted to be driven into the handle member 1 to aid in securing said bracket in effective position thereon.

It will be observed that the wire rod 5 is inwardly curved or extended intermediate of its ends or points of attachment to the movable cutter 4 and the manually actuated lever 8, whereby when said lever is depressed or actuated, said movable blade will be actuated by the minimum movement of said lever, as is apparent, thus lessening the stroke or movement required to actuate said lever.

The bracket or attaching member 9 is preferably constructed in a single piece of metal, of plate-like outline, having laterally extended end portions 10 conforming to the contour of the front edge of the staff 1, the contracted intermediate portion of said bracket between said laterally extended portions, having perpendicular portions 11 arranged parallel with each other and spaced apart, said perpendicular or outstanding portions forming ears having opposed apertures 12 therethrough to receive the pivot or fulcrum 8^a of the lever, the shank portion 7 of said lever being received between the outstanding or perpendicular portions.

The means of attachment for the bracket 9 consists preferably of headed pins or bolts 13, passing through suitable openings in the

handle 1 and through the laterally extended portions 10 of said bracket, the openings in said laterally extended portions for said bracket being formed about centrally of the same. Said attaching plate or bracket, which may be a casting, or otherwise formed, is, it is apparent, durable and effective for its purpose and is readily secured in place together with the movable blade actuating lever.

It will be noted that in applying the device for use, the handle member 1, being suitably grasped together with the lever 8, the hook 3 is lifted and caught over the limb or branch of a tree and by suitably manipulating said lever, the movable blade is forcibly engaged with the limb or branch, which will effectively sever the latter, as will be readily understood.

20. What I claim is:

1. A device of the character described, comprising a handle member having at its upper end a fixed hook-shaped blade, a movable blade pivoted to the first-referred-to blade at a point about in alinement with the rearwardly extending arm thereof, a manually actuated lever having an annular shank, a resilient connection between said cutter arm and said shank, means for bowing said resilient connection inwardly toward said handle and for the guidance of

its movement and an attaching bracket for said manually actuated lever having an intermediate contracted portion provided with parallel outstanding ears for the reception therebetween of the inner end of said shank, means for effecting pivotal connection between said shank and said ears, said bracket having upper and lower curved transverse portions embracing said handle and pointed terminals insertible in said handle and means for aiding the attachment of said bracket to said handle.

2. A device of the character described, comprising a staff or handle member having applied thereto at its upper end, a fixed cutting jaw, a movable like jaw, a lever member, means of connection between said lever and said movable jaw for actuating the latter and an attaching member consisting of a plate adapted to conform and applied to said handle member and having sharpened or pointed angular extensions projecting from its corner edges and entering or embedded in said handle member.

In testimony whereof I have signed my name to this specification in the presence of two subscribing witnesses.

ALVIN S. KLEINSMITH.
